UNITED STATES PATENT OFFICE.

CHARLES E. SARGENT, OF COELLISS, WISCONSIN, ASSIGNEE TO WISCONSIN ENGINE COMPANY, OF COELLISS, WISCONSIN, A CORPORATION OF WISCONSIN.

IGNITION MAGNETO MECHANISM FOR AIR-STARTED INTERNAL-COMBUSTION ENGINES.

Specification of Letters Patent. Patented June 14, 1910.

961,648.

Application filed July 18, 1908. Serial No. 444,181.

To all whom it may concern:

Be it known that I, CHARLES E. SARGENT, a citizen of the United States, residing at Corliss, in the county of Racine and State 5 of Wisconsin, have invented a new and useful Improvement in Ignition Magneto Mechanism for Air-Started Internal-Combustion Engines, of which the following is a specification.

10 My invention relates to certain new and useful improvements in ignition magneto mechanism for air-started internal-combustion engines, and is fully described and explained in the accompanying drawing, in 15 which:

Figure 1 is an elevation of the ignition magneto mechanism proper; Fig. 2 is a section in the line 2 of Fig. 1; Fig. 3 is a section in the line 3 of Fig. 2; Fig. 4 is a side 20 elevation of an engine showing the ignition magneto mechanism in place thereon, and the general arrangement of co-operating parts; and Fig. 5 is an end view of the engine and ignition-magneto mechanism, 25 the elevation being one of the left-hand end of the parts shown in Fig. 4.

Referring to the drawings, and more particularly in the first instance to Figs. 4 and 5, 1, 1, are the cylinders of a gas engine 30 which is provided with a fly-wheel 2, a countershaft 3 and suitable valve-mechanism. The engine here illustrated is of course only one of many types to which my invention can be applied and the form illustrated is that shown in my Patent No. 35 783,983. Inasmuch as the details of the construction of the engine form no part of the present invention, a description thereof will not be necessary at this time. In the base 40 of the engine is a reservoir 4 for compressed air into which air can be pumped by means of a pump 5, operated by a cam on the countershaft 3. This reservoir for compressed air is adapted for use in starting the 45 engine and for that purpose is led out through a pipe 6 controlled by a valve 7 to the valve-mechanism. The valve-mechanism is of such form that through it compressed air can be led to the cylinders or a 50 cylinder for starting purposes, the particular form of mechanism here illustrated being that shown in the patent above referred to, in which patent are illustrated as here two sets of cams on the left hand end of the 55 counter-shaft, which can alternately be

thrown into action by means of a hand valve 7, the valves operating as the valves of a compressed air-engine when the valve 7 is at one position, and as the valves of a four-cycle gas-engine when the hand-lever is in another position. It will be obvious, however, that as far as the present invention is concerned, the particular form of valve-mechanism is wholly immaterial, the essential point being merely that there shall be a 60 gas-engine of the type which is started by the action of compressed air in its cylinders or in a cylinder, and that there shall be in addition a supply of compressed air for such starting purposes, and means for controlling 65 the action of such compressed air.

Referring now to Figs. 1, 2 and 3, A is the main-shaft of the magneto which in its details of construction may be of any desired form suitable for producing the requisite current for the desired spark. On the shaft A is mounted an impact-bucket wheel B rigid with the shaft and adapted by its rotation to turn the shaft in the direction illustrated by the arrow in Fig. 1. 75 C is the nozzle adapted to direct a current of compressed air against the buckets of the wheel B in such direction as to produce the requisite rotation thereof. The nozzle C is connected with the pipe 6 so that when the 80 valve 7 is opened to start the engine, compressed air will issue from the nozzle C striking the buckets of the wheel B and setting the shaft of the magneto in motion. 85 Inasmuch as the magneto is comparatively light, it will reach a high speed of rotation very quickly and will be capable of supplying the requisite spark to run the engine before the engine has reached sufficient velocity to 90 run on gas. The wheel B is provided with a 95 projecting boss B¹ upon which is mounted a loose pulley D connected by means of a belt D¹ to some part rotated by the engine. A clutch connection is provided between the pulley D and the bucket-wheel B of such 100 construction that when the pulley rotates faster than the bucket-wheel the pulley will drive the magneto whilst the bucket-wheel 105 can rotate freely at a greater speed than the pulley without interference. In the particular form of mechanism which I prefer, the clutch provided is of the type shown in Fig. 3, the pulley being provided with 110 tapering depressions d in which run rollers d¹. When the pulley is running faster than

the bucket-wheel, the rollers will run to the small ends of the depressions and bind the two parts together, while when the bucket-wheel is rotating faster than the pulley, the rollers will run to the large ends of the depressions and permit relative rotation. I am aware that this is a common form of clutch mechanism and it is quite obvious that any other form accomplishing the same results might be readily substituted for the one here shown.

The operation of the device will now be readily apparent. As soon as the engine has reached its normal speed, after the air is turned on in the way already set forth, or after the engine begins to run on gas and the air is shut off, the speed of the bucket-wheel will fall below the speed of the pulley which is driven by the engine, and therefore after the engine will drive the magneto in the usual way.

The device shown and described is particularly advantageous because it enables the magneto to get in rapid and almost instantaneous operation so as to provide the requisite spark at the earliest possible moment when it can be required by the needs of the engine, and immediately upon the cutting off of the starting air, the magneto will be picked up by the engine and driven in the usual manner. The device is further advantageous because the magneto is automatically set in operation at high speed upon the movement of the main valve necessary to start the engine, and the starting power for the magneto is automatically cut off when the starting air supply is cut off.

I realize that considerable variation is possible in the details of construction of my improved device, without departing from the spirit of my invention, and I do not intend therefore, to limit myself to the specific form herein shown and described.

What I claim as new and desire to secure by Letters Patent, is—

1. The combination with an air-started internal-combustion engine and an ignition generator therefor, said generator having a movable part, of means for driving the generator from the engine, means for supplying compressed air, means connected to said supply for driving the generator by compressed air, means also connected to said supply for starting the engine by compressed air, and a single means for controlling the supply of air to the engine and the generator driving means.

2. The combination with an internal-combustion engine and an ignition-generator therefor, said generator having a movable part, of means for driving the generator from the engine, a connection between the driving means and the generator to per-

mit the generator to over-run the driving means but preventing the driving means from over-running the generator, a rotatable part adapted to be driven by compressed air fast to the movable part of the generator, and means for supplying compressed air to said rotatable part.

3. The combination with an air-started internal-combustion engine and an ignition generator therefor, said generator having a movable part, of means for driving the generator from the engine, means for driving the generator by compressed air, means for driving the engine by compressed air, a single means for controlling the supply of air to the engine and the generator driving means and means for causing the engine operated driving means of the generator to drive the generator when the engine has attained its speed.

4. The combination with the ignition-generator of an internal-combustion engine of the type started with compressed air, said generator having an armature shaft, of an impact bucket-wheel fast on the armature shaft thereof, a loose pulley having a clutching means for permitting the armature to run faster than the loose pulley but not slower, an air-nozzle directed toward the buckets of the bucket-wheel, means for connection between the loose pulley and the engine, and a pipe connecting the air-nozzle to the compressed air supply.

5. The combination with the ignition-generator of an internal-combustion engine of the type started with compressed air, said generator having an armature shaft, of an impact bucket-wheel on the shaft thereof, a loose pulley having a clutching means for permitting the armature to run faster than the loose pulley but not slower, an air-nozzle directed toward the buckets of the bucket-wheel, means for connection between the loose pulley and the engine, and a pipe connecting the air-nozzle to the compressed air supply between the engine and the valve which turns it on to start the engine.

6. The combination with an internal-combustion engine and an ignition-generator therefor, of a single source of compressed air, air actuated means for operating the ignition-generator, and connection between the source of compressed air and the engine adapted to start the latter, and between the source of compressed air and the driving mechanism for the ignition-generator, and connections between the engine and ignition-generator whereby the engine may drive the ignition-generator.

CHARLES E. SARGENT.
